(57) **CLAIM**

The ornamental design for an automobile side strake or replica thereof, as shown and described.

DESCRIPTION

FIG. 1 is a left elevation view of an embodiment of an automobile side strake or replica thereof in accordance with the present design;

FIG. 2 is a rear, left perspective view thereof;

FIG. 3 is a front, left perspective view thereof;

FIG. 4 is a front elevation view thereof;

FIG. 5 is a top plan view thereof;

FIG. 6 is a rear elevation view thereof; and,

FIG. 7 is a right elevation view thereof.

Portions of the automobile side strake or replica thereof shown in evenly spaced broken lines form no part of the claimed design.

1 Claim, 7 Drawing Sheets
